UNITED STATES PATENT OFFICE.

CHARLES AUGUSTINE, OF HERMANN, MISSOURI.

MACHINE FOR MARKING VAMPS OF SHOES.

1,391,752.

Specification of Letters Patent. Patented Sept. 27, 1921.

Application filed August 18, 1919. Serial No. 318,259.

To all whom it may concern:

Be it known that I, CHARLES AUGUSTINE, a citizen of the United States of America, a resident of Hermann, in the county of Gasconade, State of Missouri, have invented certain new and useful Improvements in Machines for Marking Vamps of Shoes, of which the following is a full, clear, and exact description, reference being had to the accompanying drawings, forming a part of this specification.

My invention relates to a machine for marking the vamps of shoes to indicate the points at which the quarters of the shoes and the tips of the shoes are to be stitched, the machine being so constructed as to provide for the marking operations being performed with respect to various sized shoes.

Figure I is a top plan view of my vamp marking machine. Fig. II is a front elevation of the machine. Fig. III is an elevation, partly in section, of the means for raising and lowering the presser plate of the machine. Fig. IV is a horizontal section taken on line IV—IV, Fig. II. Fig. V is an enlarged vertical section taken on line V—V, Fig. IX. Fig. VI is a horizontal section taken on line VI—VI, Fig. II. Fig. VII is a top view of a vamp before it is marked. Fig. VIII is a top view of a vamp after being marked in my machine. Fig. IX is a horizontal section taken on line IX—IX, Fig. II, looking upwardly from said line and showing the parts thereabove in bottom plan. Fig. X is a cross section through one of the adjustable gage-carrying blocks.

My machine may be mounted in any suitable manner, but is shown in the drawings as being supported by uprights A resting upon a bench B (see Fig. II).

1 designates the base of the machine, which is surmounted by guide posts 2, which receive sleeves 3 slidable vertically on said posts. Said sleeves have conjoined to them the presser plate 4 located at the top of the machine and arranged parallel with the base 1, the means of connection between the presser plate and the sleeves preferably comprising arms 5 carried by the sleeves, which are bolted or otherwise secured to the presser plate. Vertical movement is imparted to the presser plate by pull rods 6 extending through the arms 5 and surrounded by cushion springs 7, located above said arms, said cushion springs serving as shock absorbers when the presser plate 4 is lowered into

working position, as will hereinafter appear. A connecting rod 8, fitted to the lower ends of the pull rods 6, has pivoted to it midway of its length an operating lever 9 (see Figs. II and III), which is pivotally supported intermediate of its ends at 10 and is provided with a fork 11, which receives between its prongs a rotatable cam 12 through the medium of which the operating lever 9 is rocked to move the connecting rod 8 and the pull rod 6 for the purpose of lowering and raising the presser plate 4.

13 designates posts surmounting the base 1 and supporting a bed plate 14 recessed intermediate of its ends to form a channel 15, which is overhung at its sides by gibs 16 secured to the bed plate.

A vertically movable work plate 17, adapted to receive shoe vamps, is arranged horizontally above the bed plate 14, and is provided with elongated openings 18 and 19 through which piercing pins for marking the shoe vamps, to indicate the points at which the tips are to be stitched thereto, are adapted to operate when the work plate is lowered, as will hereinafter appear. The work plate is also provided with diagonally arranged elongated openings 20, through which piercing pins are adapted to extend for marking the shoe vamps at the points where the quarters of the shoes are to be stitched thereto, and said work plate is further provided adjacent its rear edge with notches 21, which receive gage pins to be hereinafter more particularly mentioned. The work plate 17 is directed in its vertical movements by guide pins 22 surrounded by lift springs 23 (see Fig. II), which serve to elevate said plate after it has been depressed by the presser plate 4.

24 designates a carrier block slidably arranged in the channel 15 of the bed plate 14, the side edges of said block being confined by the gibs 16. The carrier block 24 is preferably formed with a top extension 25 (see Figs. II and IV), having affixed thereto vertically disposed piercing pins 26 and 27, the pins 26 being arranged in rows extending from the side edges of the extension 25, and the pin 27 being located centrally of said extension.

It will be understood from the foregoing description that a shoe vamp to be marked is placed upon the work plate 17 and that the piercing pins 26 and 27 will move through the openings 18 and 19 in the work

plate to pierce the vamp and thus indicate, by a series of small perforations, the line on which the tip of a shoe is to be stitched to the vamp. The carrier block 24, being slidably arranged in the bed plate 14, may be moved forwardly and rearwardly in the channel of said bed plate to provide for the piercing of shoe vamps at different locations lengthwise of the vamps, the movement 5 of said carrier block being accomplished through the medium of a feed screw 28 having engagement with the carrier block to impart movement thereto when rotated, the feed screw being loosely supported in a bearing 29 arranged on the bed plate 14 at the rear of the carrier block. A pointer 30, extending forwardly from the carrier block 24, is operable along a scale plate 31 supported by the bed plate 14, said pointer and 10 scale plate serving to indicate to the operator of the machine the degree to which the carrier block is moved according to desired puncturing of a vamp to indicate the tip line. A set screw 32, extending through one side 15 of the bed plate 14 to the channel 15 therein, is adapted to engage the side edge of the carrier block 24 to hold said block in fixed 20 position.

Proceeding now to description of the 25 means in my machine for marking the points at which the quarters of shoes are to be stitched to the vamps: 33 designates adjustable guides extending diagonally in the channel 15 of the bed plate 14 back of the carrier 30 block 24, these guides diverging outwardly and rearwardly at angles relative to each other, and being pivotally connected to the bed plate at their front outer corners by pivot screws or pins 34. The guides 33 are 35 provided with longitudinal dovetail channels 35, formed in part by gibbs 35' (see Fig. X), and are adapted to be held from movement on their pivots by set bolts or screws 36, which extend through slots 37 in the bed 40 plate 14 (see Fig. IX), said bolts or screws 45 serving to hold the guides at different angles relative to each other for a purpose which will be hereinafter made plain.

38 are slide blocks operable upon and 50 within the channels of the guides 33 and slidable longitudinally of said guides by means to be presently described. Upon the slide blocks 38 and preferably seated in channels therein, as seen most clearly in 55 Fig. X, are adjustable plates 39 provided with longitudinal slots 39', which receive set screws 40, thereby permitting backward and forward movement of the plates 39 relative to the slide blocks 38 and the main- 60 tenance of said adjustable plates in set positions on said slide blocks. Projecting upwardly from the forward ends of the adjustable plates 39 adjacent their inner sides are vertical gage pins 41, preferably of 65 sufficient height to extend through the work

plate 17 and also through the presser plate 4, said pins occupying the notches 21 in the work plate. Said adjustable plates 39 are also provided at their forward ends with piercing pins 42, which are located adjacent 70 the outer sides of the plates and are adapted to project through the elongated openings 20 in the work plate 17 when said work plate is lowered. Said piercing pins 42 serve to mark the shoe vamps to indicate the 75 points at which the quarters are to be stitched to the vamps.

The slide blocks 38 are moved backwardly and forwardly in the guides 33 by means located beneath the bed plate 14, which will 80 next be described. The guides 33 are provided with longitudinal slots extending through their bottoms which receive pins 43 having connected thereto links 44 (see Figs. IX and X). Said links are pivoted to a 85 sleeve 45 having a screw threaded bore therein, which receives an adjusting screw 46 arranged in bearings 47 and 48 attached to the bottom of the bed plate 14. The adjusting screw 46 is provided with a graduated head 90 49 preferably grooved annularly and into juxtaposition with which a pointer arm 50, carried by the scale plate 31, extends.

By turning the adjusting screw 46 the 95 sleeve 45 may be moved either forwardly or backwardly, and the slide blocks 38 are therefore moved correspondingly to vary the positions of the gage pins 41 and the piercing pins 42. The object in thus moving the slide blocks is to properly position the pins 100 41 and 42 for the vamps of different sized shoes and different styles of shoes. Suitable characters may be used upon the graduated head 49 of the adjusting screw 46 to indicate to the operator the proper movement of said 105 adjusting screw to attain a desired adjustment of the slide blocks 38, and the pins 41 and 42 carried thereby.

The angles of the guides 33 relative to each other are altered to move the pins 41 110 and 42 outwardly or inwardly according to different widths of vamps by the following means. An adjusting screw 51, operable in lugs 52 and 53 on the bed plate 14, extends 115 through, and has screw threaded engagement with, a spreader 54, which bears against the inner sides of the guides 33. Said guides are joined at their rear ends by a spring 55, which tends to draw the guides toward each other when they are freed of 120 the restraint offered by the bolts 36. After loosening the bolts 36, the guides may be spread apart through the operation of the spreader 54 in a forward direction, whereas when the spreader is moved rearwardly the 125 spring 55 tends to draw the guides toward each other. The guides 33 are provided with pointers 56 extending from their rear ends and adapted to traverse scale characters on the bed plate 14, which serve to in- 130

dicate to the operator the degree to which the guides are adjusted according to desired positioning of the gage pins 41 and the piercing pins 42.

- 5 To provide for the use of my machines in marking vamps to which tips are not to be applied but to indicate only the points at which the quarters are to be sewed, I make the channel 15 in the bed plate 14 of greater 10 height than the portion of the carrier block 24 occupying said channel, thereby permitting the introduction of lift strips 57 between the bed plate and the carrier plate. Said lift strips are removably held beneath 15 the carrier plate 24 by spring tongues 58 or other suitable detents, which permit the ready withdrawal of the strips and the lowering of the carrier plate, so that the piercing pins 26 and 27 carried thereby will 20 not be projected through the work plate 17 to pierce the vamps of shoes to which tips are not to be applied.

Fig. VII shows a vamp as it appears before being marked in my machine, and Fig. 25 VIII shows the vamp as it appears after being pierced by the pins 26, 27, and 42. The pierced holes in the vamp shown in Fig. VIII nearest the toe of the vamp are formed by the pins 26 and 27 to indicate the 30 stitching line for the tip, and the pierced holes at the rear of the vamp, formed by the pins 42, indicate the points for the attachment of the quarter of the shoe to the vamp.

I claim:

35 1. A shoe vamp marking machine comprising piercing pins for marking a vamp at its tip and quarter receiving portions, a vamp support above said piercing pins, and means for moving said vamp into engagement with said pins.

2. A shoe vamp marking machine comprising piercing pins for marking a vamp at its tip and quarter receiving portions, a vamp support above said piercing pins, and 45 a presser member by which said vamp support may be depressed to cause said pins to mark said vamp.

3. A shoe vamp marking machine comprising piercing pins, a vamp support yieldingly supported above said piercing pins, and a presser member by which said vamp support may be depressed to cause said pins to mark said vamp, said vamp support having vamp supporting faces at opposite sides 55 of said pins.

4. A shoe vamp marking machine comprising a vamp support, a piercing pin carrier adjustably slidable relative to said support, means for adjustably sliding said carrier, piercing pins on said carrier, and means for depressing said vamp support for causing said piercing pins to be projected into a vamp resting on said support.

5. A shoe vamp marking machine comprising a vamp support, piercing pins be-

neath said vamp support adapted to be projected therethrough, a plurality of adjustable gage members for regulating the positioning of vamps on said support, and means for causing said piercing pins to be 70 projected into a vamp resting on said support.

6. A shoe vamp marking machine comprising a vamp support, a plurality of adjustable gage means for regulating the positioning of vamps on said support, piercing pins adapted to be projected through said vamp support to mark a vamp resting thereon, and means for moving said vamp into 75 engagement with said pins for causing said 80 piercing pins to be projected into the vamp.

7. A vamp marking machine comprising a slotted vamp support, piercing pins adapted to be projected through said vamp support, and means for raising said piercing 85 pins into operative position, said means being removable to allow the piercing pins to be restored into inoperative positions.

8. A shoe vamp marking machine comprising a vamp support, gage members 90 adapted to regulate the positioning of the vamps on said support, vamp marking means movable with said gage members and adapted to be projected through said vamp, and support for said gage members movable 95 laterally relative to said vamp supports.

9. A shoe vamp marking machine comprising a vamp support, means for regulating the positioning of vamps on said support, said means being adjustable to suit different 100 sized vamps, vamp marking means movable with said regulating means adapted to be projected through said vamp support, and means for adjustably moving said vamp marking means to cause them to be projected 105 through the vamp support in varying positions.

10. A vamp marking machine comprising a vamp support, vamp marking means adapted to be projected through said vamp support, guides pivotally mounted beneath said vamp support, slides movable through said guides, vamp marking means carried by said slides, and means for moving said vamp support relative to said marking 110 means whereby the marking means are projected through said vamp support.

11. A shoe vamp marking machine comprising a vamp support, means adapted to be projected through said vamp support to 115 mark the vamps resting thereon, means for moving said projecting means through said vamp support, guides pivotally mounted beneath said vamp support, means supported by said guides for regulating the positioning of the vamps on said support, means for moving said guides outwardly relative to each other, and a spring for moving the guides in the opposite direction.

12. A shoe vamp marking machine com-

prising a vamp support, vamp marking means adapted to be projected through said vamp support, means for moving said support relative to said marking means, a pair of guides pivotally mounted beneath said vamp support and arranged diagonally relative to each other a spreader operable between said guides to separate them, a spring connecting the guides adapted to move them in an opposite direction relative to the direction in which they are moved by said spreader, gage pins adjustably supported by said guides, and vamp marking means movable with said gage pins.

15 13. A vamp marking machine comprising

a vamp support, vamp marking means beneath said support adapted to be projected therethrough, means for projecting said marking means through said support, removable means beneath said vamp marking means adapted to be withdrawn to permit the lowering of said vamp marking means to inoperative positions, and separate vamp marking means operable for marking operation when the first named vamp marking means are in inactive positions.

In testimony that I claim the foregoing I hereunto affix my signature.

CHARLES AUGUSTINE.
